[57] CLAIM

The ornamental design for a combination beach towel-carry bag, as shown and described.

DESCRIPTION

FIG. 1 is a front elevational view of a combination beach towel-carry bag showing my new design;

FIG. 2 is a left side elevational view thereof;

FIG. 3 is a view similar to FIG. 1 with the bag in a partially folded condition and with the upper bag portion open;

FIG. 4 is a view similar to FIGS. 1 and 3 with the bag in a further folded and rolled condition;

FIG. 5 is a top plan view with the bag in a fully folded and rolled condition and with the upper bag portion in closed condition; and

FIG. 6 is a front elevational view of the bag in the condition shown in FIG. 5.

The bottom of the bag is plain and unornamented.

FIG. 1.

FIG. 2.

FIG. 3.

FIG. 4.

FIG. 5.

FIG. 6.
